UNITED STATES PATENT OFFICE.

HARVEY MAY STRONG, OF DES MOINES, IOWA, ASSIGNOR TO PERKINS MANUFACTURING COMPANY, OF DES MOINES, IOWA, A CORPORATION OF IOWA.

SIGHT-FEED OIL-PUMP FOR USE ON AUTOMOBILES AND MOTOR-VEHICLES.

1,178,762.

Specification of Letters Patent. Patented Apr. 11, 1916.

Application filed July 22, 1915. Serial No. 41,380.

To all whom it may concern:

Be it known that I, HARVEY MAY STRONG, a citizen of the United States, residing at Des Moines, in the county of Polk and State of Iowa, have invented a new and useful Sight-Feed Oil-Pump for Use on Automobiles and Motor-Vehicles, of which the following is a specification.

My invention relates to a sight feed oil pump for use on automobiles and motor vehicles, and is operated by a lever arm resting on the valve tappet, the movements of the lever arm being controlled by power derived from the valve tappet and a spring; and the objects of my invention are, first, to provide a simple, efficient and inexpensive means for constantly and automatically indicating, while the engine, or motor, is being operated, the presence or absence of lubricating oil in the crank case, or oil reservoir, from the interior of the vehicle; second, to provide a means of automatically distributing lubricating oil to the several moving parts of the motor, or engine; third, by so placing my mechanism to provide a means for preventing wastage in the use of lubricating oil by directing all leakage back into the crank case, or oil reservoir; fourth, to so construct and assemble my mechanism as to make instalment thereof on an automobile or motor vehicle easy and expeditious; fifth, to operate my mechanism by power derived from the valve tappet and the expansion of the piston return spring; sixth, to so arrange all parts of my mechanism as to provide constant lubrication thereof without the use of oil cups or other lubricating devices. I attain these objects by the mechanism illustrated in the accompanying drawing, in which—

Figure 1, is a cross section of the lever arm with the lower end in place and resting on the valve tappet, the pump, and T with ball checks including portions of intake and exhaust pipes; Fig. 2, is a top view of the lever arm held in place by the yoke and bearing pin together with a portion of the cylinder valve cover, or plate, and attached thereto is the T and portions of each of the intake and exhaust pipes; Fig. 3 shows a side elevation of an engine with my oiler installed thereon, parts of the engine casing being broken away, the parts being shown in

section; Fig. 4, is an indicator placed preferably on the dash board or within the vision 55 of the operator of the automobile or motor vehicle with intake and exhaust connections.

Similar letters refer to similar parts through the several views.

In the accompanying drawings, the reference numeral 10 is applied to the removable valve cover member found on some internal combustion engines and particularly on the engine now used on Ford cars. On the valve inclosure is an outwardly projecting 65 casing 10 forming a chamber 11. Pivotaly mounted in the lower portion of the chamber 11 is a lever C preferably of the bell crank type with its arms extending away from the pivotal point of the lever at an 70 acute angle with relation to each other, as shown in Fig. 1. The lever C may be of different forms and may be pivoted in any suitable way, but as shown is pivoted on a pin D extending through the arms of a yoke 75 E within the chamber 11. The yoke E has a cylindrical portion 12 extending outwardly through the wall of the casing 10. The outer end of the cylindrical portion 12 is screw-threaded to receive a nut F. 80

The casing 10 is located and arranged as to receive part of the pump, and the operating lever so that said parts do not interfere with the operation of the valve tappet, stem and spring. The lower arm of the bell crank 85 lever C extends inwardly and rests upon the valve tappet B. The arm of the lever which rests upon the valve tappet is preferably forked to permit free movement of the valve stem end in the space between the forked 90 portions of said lever arm.

Extending outwardly from the upper portion of the wall of the casing 10 is a cylinder H having a closed outer end. The outer end may be covered by a screw cap or cover J. 95 Slidably mounted within the cylinder H is a piston G, the inner end of which is adapted to engage the upper arm of the lever C. Received within the cylinder H is a coil spring M which abuts against the cap J and the piston G for normally yieldingly holding the upper arm of the lever C inwardly and the lower arm of said lever downwardly. For convenience I have called the spring M the piston return spring. 100 105

Communicating with the interior of the

cylinder H is one passage of an ordinary T coupling K. Connected with the other two passages of the T coupling K are intake and discharge pipes Q and P respectively, in which are ordinary check valves 13. The pipe Q is designed to be connected with the lower part of the crank casing of the engine, which forms an oil reservoir 20, while the pipe P communicates with the upper portion of the sight feed oil indicator R, which may be of any suitable construction, and is designed in the case of motor vehicles, to be mounted on the dash 21 where it will be in plain sight of the driver. Communicating with the lower portion of the sight feed oil indicator is an exhaust pipe S designed to discharge into the upper portion of the crank casing at 22. This mechanism is preferably operated by power derived from the valve tappet and piston return spring. The upward movements of the valve tappet raise the lower end of the lever arm, forcing the upper end against the pump piston and compressing the piston return spring. The downward movements of the valve tappet release the compression on the spring, whereupon the pump piston is forced out against the lever arm, thereby causing the lower end of the lever arm to follow the valve tappet on its returning movements. The spring M might be dispensed with and by properly connecting the upper lever arm with the piston, the spring on the valve stem will operate the piston in one direction. The piston being forced out in this manner creates a suction in pump cylinder H which draws the lubricating oil up from the crank case through intake pipe Q past the lower ball check (which is also raised by the suction created) into H and K. The upward movements of the valve tappet resulting in the compression of the oil in the pump cylinder and T K, force the lubricant from the pump cylinder and T past the upper ball check into exhaust pipe P, and from there into the indicator, from whence it retires through pipe S to the crank case being directed into the fore end thereof for reasons that will be hereinafter set out.

The tappet B is the usual and ordinary tappet found in automobiles and motor vehicles generally, and is part of my mechanism only in so far as motive power to operate the mechanism is derived therefrom. This mechanism may be operated by power from any of the valve tappets found in the automobile or motor vehicle, but I prefer the rear or hindmost cylinder with its corresponding tappet so as to shorten pipe lines to and from the indicator, and so as not to interfere with other parts of the motor.

The open end of the pump cylinder, as shown by the drawing in Fig. 1, is placed so that any leakage therefrom falls back into the crank case, and is, accordingly,

saved. The open end of the pump being placed immediately above the bearing pin through lever arm C provides for its lubrication since practically all leakage from the pump first falls on the pin after leaving the pump. The end of the lever arm resting on the valve tappet is lubricated by the connecting rods 23 of the engine splashing the lubricant on the valve tappet. The other and upper end of the lever arm coming in direct contact with the pump piston is always lubricated by the constant leakage from the pump.

Pipe S carries the returning lubricant to the fore end of the crank case from whence it passes through the succession of connecting rod drip cups 24 to the rear end of the crank case which is the lowest part, thereby insuring constant lubrication of the forward cylinders of the engine. Lubrication of the forward cylinders under exclusively gravity systems of lubrication is obviously impossible when the automobile or motor vehicle is ascending an incline steep enough to place the lower end of the pipe carrying the lubricant higher than the intake end. This result is achieved by making R airtight, the lubricant being pumped through the exhaust pipe from the indicator rather than passing through it as a flow superinduced by gravitation.

While in the drawings of my mechanism the lever arm C appears resting on the valve tappet and inserted between the tappet and the valve stem, I have found by recent experimentation that better results are secured, and at the same time mechanism is more readily installed by forking the lower end of the lever arm, permitting the tines of the fork to rest on the valve tappet, which is greater in diameter than the valve stem, and allow the valve stem to operate in the hollow portion between the tines of the fork as previously referred to. By this method of construction and installation it is not first necessary to remove a portion of the valve stem to permit of the insertion of the lever arm between the stem and the tappet. Lever arm C may be attached directly to either the tappet or the stem, but I prefer to rest it on the tappet as stated. My method of constructing and installing the lever arm interferes in no way with the functions of the stem and tappet and they perform unimpeded their functions with my mechanism attached.

My mechanism is made with cylinder valve cover 1 a part thereof. Although the valve covers vary in size and shape with the different kinds and makes of automobiles and motor vehicles this situation may be easily met by changing the size and shape of the covers. The casing 10 on the cylinder valve cover may be so cast with respect to width as to eliminate yoke E as a sepa-

rate part, the sides of the bulge when set apart sufficiently to accommodate the lever arm serving the same function as the yoke. When the bulge is so cast nut F also may be eliminated.

For clearness of description, I wish to state that the words "crank case" and "oil reservoir" as used throughout this specification refer to one and the same mechanical part of the automobile or motor vehicle, and mean the compartment in which is placed the oil that lubricates the moving parts of the engine. I also wish to state that the words "motor" and "engine" mean one and the same thing and refer to the mechanical part of the automobile or motor vehicle from which power to operate the same is derived.

Any convenient form of indicator carrying out the principles of the above description may be used as a part of my mechanism, and I do not wish to limit myself to the exact form of an indicator shown in the accompanying drawings.

I am aware that prior to my invention sight feed oil pumps were operated in conjunction with the motor in automobiles and motor vehicles generally by power derived from the motor. I therefore do not claim such combination broadly; but

30 I claim:

1. In a sight feed oil pump, the combination of a pump cylinder, intake and discharge pipes connected therewith, the intake pipe being adapted to be connected with an oil reservoir, a sight feed oil indicator, said discharge pipe being connected with the upper portion thereof, an exhaust pipe leading from the lower portion of said indicator, a piston slidably mounted in said cylinder, a spring in said cylinder abutting against the piston and against a part of said cylinder, and means designed to be operatively connected with a valve tappet whereby the movement of said valve tappet in one direction will impart motion to said piston in a direction for compressing the spring.

2. In a sight feed oil pump, the combination of a pump having a cylinder and a piston, with a spring adapted to yieldingly hold the piston at one limit of its movement, a T coupling having one passage communicating with said cylinder and having other passages communicating respectively with intake and discharge pipes, check valves on opposite sides of said first passage, said intake pipe being adapted to communicate with an oil reservoir, a sight feed oil indicator, said discharge pipe communicating with the upper end thereof, an exhaust pipe leading from the lower end of said indicator, and a lever fulcrumed adjacent to said pump and having one arm adapted to engage one end of the pump cylinder, and the other arm adapted to be operated in one direction by the valve tappet of an engine for

moving said piston against the pressure of said spring, whereby when an engine is operated and moves said valve tappet said pump will be operated thus forcing lubricant from said oil reservoir through said sight feed oil indicator.

3. In a sight feed oil pump, a pump adapted to be mounted on an engine, having a cylinder open at one end and a piston, a spring mounted in said cylinder and designed to abut against a part of the cylinder and against the piston, a lever pivoted below the open end of the cylinder and adapted to be lubricated at its pivotal point and at its point of contact with the piston, by leakage from the pump, having one arm adjacent to an end of the piston and the other arm adapted to be operated by a valve tappet, a T coupling having one passage communicating with the closed end of said cylinder, intake and discharge pipes communicating with the other passages of said T coupling, check valves on opposite sides of said first passage, a sight feed oil indicator, the upper part of which communicated with said discharge pipe, an exhaust pipe leading from the lower part of said indicator, said intake pipe being adapted to communicate with an oil reservoir.

4. In a sight feed oil pump, a pump designed to be supported adjacent to the valve tappet of an engine, comprising a cylinder, having an open inner end projecting into the casing of the engine, a piston mounted in said cylinder, a spring in said cylinder abutting against the piston and against one end of the cylinder, a lever pivoted below the open end of said cylinder having one end adapted to engage said piston and the other end adapted to be engaged by the valve tappet of the engine, a T coupling having one passage communicating with the outer end of the cylinder, intake and discharge pipes communicating with the other passages of the T coupling, check valves on opposite sides of the first passage of the T coupling, a receptacle having a transparent portion, said discharge tube communicating with the upper part of said receptacle, and an exhaust tube leading from the lower part of said receptacle, said intake pipe being adapted to communicate with the oil reservoir, the parts being so arranged that the pivot point of the lever and its point of contact with the piston will be lubricated by leakage from the pump and the part of the lever in engagement with the valve tappet will be lubricated by the movement of the engine parts.

5. In a device of the kind described, a pump comprising a cylinder mounted on an engine casing, having an open end on the interior of the casing, a piston mounted for reciprocation within the cylinder, a spring in said cylinder for yieldingly holding said

piston at one limit of its movement, intake and discharge pipes communicating with said cylinder, a lever pivoted adjacent to said cylinder having one end adapted to be engaged by the valve tappet of an engine, and the other end in operative relation with said piston, said intake pipe being designed to communicate with the crank case of an engine, the parts being so arranged that any oil leaking from the pipe will be discharged on the interior of the engine casing.

6. In a device of the kind described, a pump designed to be mounted adjacent to the valve tappet of an engine, comprising a cylinder and a piston, a lever pivoted adjacent to said pump having one end adapted to be operated in one direction by the valve tappet of an engine, the other end being arranged in operative relation to the piston, and means for operating said lever in the opposite direction.

7. In a device of the kind described, the combination with an engine having an oil reservoir, moving parts therein, with a pump adapted to pump oil from the lower portion of said reservoir to the upper portion thereof, said pump having a piston, a lever arranged in operative relation with the valve tappet of the engine and with said piston, whereby the said lever is operated in one direction for moving the piston in one

direction, and means for moving the lever in the opposite direction.

8. In a device of the kind described, the combination with an engine having a valve tappet, an oil reservoir, with a pump arranged adjacent to said valve tappet, and having means for operating the piston in one direction from said valve tappet, means for operating the piston in the opposite direction, and means for operatively connecting said pump with said oil reservoir whereby oil is pumped from the lower portion of the oil reservoir to an upper portion thereof.

9. In a device of the kind described, the combination with an engine having a valve tappet, an oil reservoir, with a pump arranged adjacent to said valve tappet, and having means for operating the piston in one direction from said valve tappet, means for operating the piston in the opposite direction, and means for operatively connecting said pump with said oil reservoir whereby oil is pumped from the lower portion of the oil reservoir to an upper portion thereof, said last described means including a sight feed oil indicator.

HARVEY MAY STRONG.
